SHIELD FOR COFFEE MACHINE BURNER PLATES

James O. Tate, Birmingham, Ala., assignor to
Tate, Inc., Birmingham, Ala.

Filed Jan. 8, 1973, Ser. No. 321,728

Term of patent 14 years

Int. Cl. D15—08

U.S. CL. D55—1 E

FIG. 1

FIG. 2

FIG. 3

FIG. 4

FIG. 1 is a top plan view of a shield for coffee machine burner plates showing my new design;

FIG. 2 is a front elevational view thereof;

FIG. 3 is a left end elevational view thereof, the right end being a mirror image; and

FIG. 4 is a cross-sectional view taken on line 4—4 of FIG. 1.

I claim:

The ornamental design for a shield for coffee machine burner plates, substantially as shown and described.
